UNITED STATES PATENT OFFICE.

JOHN H. FARREL, OF CAMDEN, NEW JERSEY, ASSIGNOR TO HENRY W. MAYBAUM, OF PHILADELPHIA, PENNSYLVANIA.

POCKET-LAMP.

SPECIFICATION forming part of Letters Patent No. 439,578, dated October 28, 1890.

Application filed June 19, 1890. Serial No. 356,007. (No model.)

To all whom it may concern:

Be it known that I, JOHN H. FARREL, a citizen of the United States, residing at Camden, in the county of Camden and State of New Jersey, have invented certain new and useful Improvements in Pocket-Lamps, of which the following is a specification.

My invention relates to that class of lighting devices designated as "pocket-lamps," provided with devices for feeding and exploding by frictional contact with a device, a fulminating pellet or cap applied to a tape, strip, or ribbon to ignite means concealed within a housing.

15 The principal objects of my invention are, first, to provide a cheap, compact, reliable, and convenient lamp adapted to be carried in the pocket with perfect safety, and, second, to provide a pocket-lamp adapted to contain a narrow strip or ribbon having fulminating-pellets or percussion-caps applied thereto, and fed by simple and effective means to cause not only the pellets or caps thereof to be exploded by frictional contact 20 with a scratcher to ignite a light-producing appliance in connection with the lamp, but also to permit the used strip, tape, or ribbon to be wound up, so that it may be easily removed for the insertion of another strip, tape, 25 or ribbon provided with caps or pellets.

My invention consists of a pocket-lamp adapted for the employment of a suitable tape, strip, or ribbon having fulminating pellets or caps applied thereto, and the device 30 constructed, arranged, and adapted for operation substantially in the manner herein-after described.

The particular characteristic features of the invention will be more fully understood 35 from the accompanying drawings, forming part hereof, and in which—

Figure 1 is a perspective view of a pocket-lamp embodying the features of my invention and showing the housing thereof in an 40 open position, with the narrow strip, tape, or ribbon provided with fulminating pellets or caps mounted therein; and Fig. 2 is a similar view of a lamp, showing the two-part housing in a closed position, with its cover thrown 45 back and in a position to permit of the actuation of the toothed disk for causing the tape,

strip, or ribbon to be fed and ignited by frictional contact with a scratcher disposed adjacent to the wick of the lamp to produce a flame thereat.

55

Referring to the drawings, A is the divided and recessed housing of the lamp provided with a receptacle a, adapted to receive oil and an absorbent material or substance, and said receptacle provided with a hinged cover a'. This cover is provided with a tube a², adapted to permit of the insertion therethrough of a wick a³, held in the receptacle in contact with fibrous material immersed or saturated with a suitable oil for maintaining 60 the wick in a condition to readily permit of its being ignited or lighted at the exposed end of the tube a² in a manner to be herein-after fully described.

b is a retaining pin or lug secured to the 70 wall a⁴ of the oil-receptacle a.

c is a stud-pin secured to the wall of said oil-receptacle and provided with a loose sleeve c'.

d is a toothed disk mounted on a pin d', 75 secured into the wall of the oil-receptacle a. This toothed disk d is arranged so that a portion thereof will project beyond the recessed portion of the two-part housing of the lamp.

e is a curved spring adapted to normally 80 engage with the toothed disk d to prevent said disk from being turned in a reverse direction. The pin d' of the disk d is bifurcated for a purpose to be presently described.

f is a stationary scratcher attached to the 85 hinged cover a' of the oil-receptacle a.

g is a narrow strip or ribbon of muslin, linen, or other suitable material provided with percussion-caps or fulminating-pellets g', disposed at suitable distances apart along the 90 same. The narrow tape, strip, or ribbon g, formed into a coil, is inserted onto the retaining pin or lug b and then led around the loose sleeve c' of the stud-pin c, and the forward end thereof coiled around and between 95 the bifurcated pin d', as shown in Fig. 1, and the divided housing then closed, as shown in Fig. 2, with its cover A' thrown rearward and with the latch a⁷ of one part of the housing caused to engage in the small recess or opening a⁸ in the wall of the oil-receptacle a. The disk d is then actuated by the thumb or in 100

- any other preferred manner, and the narrow strip or ribbon fed upward from the retaining-pin *b* around the loose sleeve *c'* of the stud-pin *c*, where the individual caps or pellets of the narrow strip or ribbon *g* are brought by the operation into frictional contact with the stationary scratcher *f*, thereby causing the same to be exploded and the wick *a'* at the exposed end of the tube *a* to be lighted.
- 5 10 The tape, strip, or ribbon *g*, after its caps or pellets have been exploded simultaneously with the feeding of the same, is wound around the bifurcated pin *d'* of the toothed disk *d* until the entire strip has been rendered useless by the consumption of all of the caps or pellets thereof, when the strip or ribbon may be readily removed and another inserted by simply causing the lamp to assume a position, such as is illustrated in Fig. 1.
- 15 20 In the manufacture of the strips or ribbons it will of course be understood that the pellets or caps thereof should be omitted for a short distance from the extremal portion of the tape, strip, or ribbon, in order that all 25 possibility of accident or explosion in the insertion of the same around and between the bifurcated pin *d'* of the toothed disk *d* may be obviated. The stud-pin *c*, instead of being provided with a loose sleeve *c'*, may be 30 formed integral therewith, and, moreover, this sleeve is preferably milled in the direction of its length to insure greater certainty in action in the feeding of the strip or ribbon for presenting the individual pellets or caps thereof 35 to the scratcher *f*.
- Having thus described the nature and objects of my invention, what I claim as new, and desire to secure by Letters Patent, is—
1. A pocket-lamp provided with a divided 40 housing and cover, an oil-retainer therein having a wick-holder and scratcher, a retainer adapted to hold a narrow percussion-tape, strip, or ribbon, a stud-pin supported adjacent to said scratcher for said tape, strip, or 45 ribbon to travel over, and a toothed disk extending through the casing at one side and adapted to permit of said tape, strip or ribbon being caused to frictionally contact with

said scratcher and the said disk provided with a pin adapted to permit of said tape, 50 strip, or ribbon being wound thereon, substantially as set forth.

2. A pocket-lamp provided with a two-part housing and a hinged cover, an oil-retainer adapted to support in position a wick and 55 scratcher, a pin or lug adapted to hold a narrow tape, strip, or ribbon provided with caps or pellets, a stud-pin provided with a milled sleeve, a toothed disk journaled in said housing and provided with means adapted to permit of said tape, strip, or ribbon being wound thereon, and a spring normally engaging with a tooth of said disk, substantially as and for the purposes set forth.

3. A pocket-lamp provided with a divided 60 housing, an oil-absorbent retainer therein provided with a tube adapted to expose a wick, a scratcher, a retaining-pin, a tape, strip, or ribbon provided with fulminating pellets or caps mounted thereon, a pin provided with a 70 sleeve, a toothed disk partially exposed beyond said housing and provided with means to permit of said tape, strip, or ribbon being wound thereon, and a spring to prevent a reverse movement of said disk, substantially as 75 and for the purposes set forth.

4. A pocket-lamp provided with an oil and absorbent material receptacle having a wick-tube and a scratcher, a retainer located in the lower part of the lamp-casing, a toothed 80 disk extending through one side of said casing and provided with a pin or lug adapted to receive an ignitable strip, tape, or ribbon, a stud-pin in the upper part of said casing having a loose sleeve mounted thereon, and 85 said disk by the actuation thereof causing said strip, tape, or ribbon to contact with said scratcher, substantially in the manner set forth.

In witness whereof I have hereunto set my 90 signature in the presence of two subscribing witnesses.

JOHN H. FARREL.
